[57] CLAIM

The ornamental design for a garment bag, substantially as shown and described.

DESCRIPTION

FIG. 1 is a front elevational view of a garment bag illustrating my new design;

FIG. 2 is a top plan view thereof, an intermediate portion of the carrying strap being broken away and omitted for convenience of illustration;

FIG. 3 is a side elevational view thereof, the opposite side being substantially a mirror image thereof, an intermediate portion of the carrying strap being broken away and omitted for convenience of illustration;

FIG. 4 is a rear elevational view thereof;

FIG. 5 is a bottom plan view thereof, an intermediate portion of the carrying strap being broken away and omitted for convenience of illustration;

FIG. 6 is a front elevational view of the garment bag shown in FIG. 1; with an upper flap in a raised position to expose the front surface of the bag beneath the flap; and

FIG. 7 is a perspective view of the garment bag shown in FIG. 1, in a folded condition.
